CLAIM

The ornamental design for a caster with brake, as shown and described.

DESCRIPTION

FIG. 1 is a perspective view of a caster with brake, showing our new design;

FIG. 2 is another perspective view thereof;

FIG. 3 is a front view thereof;

FIG. 4 is a rear view thereof;

FIG. 5 is a left side view thereof;

FIG. 6 is a right side view thereof;

FIG. 7 is a top plan view thereof; and,

FIG. 8 is a bottom plan view thereof.

The claim is directed to shaded surfaces. The broken lines immediately adjacent shaded surfaces represent the bounds of the claimed design and forms no part of the claimed design; all other broken lines in the drawings depict portions of the caster with brake that forms no part thereof.
